(57) CLAIM

The ornamental design for basketball footwear with stylized aircraft features, as shown and described.

DESCRIPTION

FIG. 1 is a top front perspective view of basketball footwear with stylized aircraft features, showing our design;

FIG. 2 is a rear view thereof;

FIG. 3 is a front view thereof;

FIG. 4 is a right view thereof;

FIG. 5 is a left view thereof;

FIG. 6 is a top view thereof; and,

FIG. 7 is a bottom view thereof.
